tion of Delaware

No Drawing. Application May 1, 1943,
Serial No. 485,335

4 Claims. (Cl. 196—96)

This invention relates to the treatment of light hydrocarbons, such as naphtha and gasoline, to effect desulfurization, and to improve the anti-knock quality and susceptibility to anti-knocking agents, such as tetraethyl lead, for the purpose of improving the hydrocarbons for motor fuel.

In accordance with the invention, the naphtha is contacted with adsorptive clay, such as fuller's earth, under conditions which I choose to term "depolymerizing" conditions. In prior practice, naphtha stocks have been treated for desulfurization and improvement in lead susceptibility by contacting with clay catalysts, usually at temperatures within the range of about 650—750° F. In the treatment of cracked naphtha stocks which ordinarily contain quantities of readily polymerizable olefins, difficulties have been encountered in this catalytic process, due to the fouling of the catalyst by means of the ultimate products of polymerization which deposit on the catalyst and shorten the catalyst life. I have discovered that if the temperature of the treatment with the adsorptive clay be sufficiently high and the time of reaction properly limited, desulfurization, increase in anti-knock quality and improvement in lead response may be accomplished under essentially depolymerizing conditions, such that there is no rapid fouling of the catalyst, with the result that the life of the catalyst may be greatly increased. It would be expected that by going from relatively moderate temperatures, such as 650—750° F., to materially higher temperatures, the tendency for deposits on the catalyst would be greatly accentuated. Contrary to such expectations, I have discovered that by carrying on the treatment at temperatures as high as 900° F., and by sufficiently limiting the time of contact with the catalyst, polymerization is so retarded or prevented, and deposition of coke or carbonaceous material on the catalyst is so reduced, that the life of the catalyst is greatly prolonged.

equilibrium is established under which any tendency toward polymerization is offset by a reversion back to the prepolymerized state, with the result that the operation may be conducted for 5 extended periods of time without substantial deposition of the ultimate products of polymerization on the catalyst and without material impairment of the activity of the catalyst.

In practicing the invention, the naphtha stock 10 is rapidly raised to a temperature of the order of 900° F. and passed through a bed of adsorptive clay, such as fuller's earth, with a time of contact with the catalyst amounting to approximately 5—15 liquid volumes of feed per hour per volume of catalyst. Under these conditions reactions take place involving conversion of sulfur compounds into hydrogen sulfide, isomerization of olefinic hydrocarbons and conversions or rearrangements of molecules functioning to increase anti-knock quality and lead response. The process is preferably conducted at relatively low pressures, such as approximately atmospheric pressure or moderate superatmospheric pressures.

In an example of the invention, a naphtha 25 stock consisting of approximately 80 per cent cracked naphtha and 20 per cent high sulfur, straight-run naphtha was rapidly passed through a heating coil thence into a contacting chamber wherein it was passed through a bed of Riverside 30 fuller's earth at a temperature of 950° F., with a space velocity of 10. The following table gives the clear octane number of the charge naphtha, the octane number of the charge naphtha with 3 cc. of tetraethyl lead added, the weight per cent of the sulfur content, and the distillation test, and also the clear and leaded octane values, the sulfur contents (determined after washing with a caustic soda solution to remove hydrogen sulfide), the weight per cent of the sulfur reductions, and the distillation tests, on various samples of the treated product, taken during various 35 periods of the run:

Charge	Product						
	0-6 hrs.	46-54 hrs.	62-70 hrs.	158-166 hrs.	211-235 hrs.	259-283 hrs.	307-331 hrs.
Octane—C. F. R. M.	64.1	70.4	65.9	66.3	68.1	66.5	66.9

E. P.	420	442	424	421	424	421	400

It appears that under these conditions of treatment a depolymerizing condition is actually established and maintained. Apparently the condition is not merely one of non-polymerization. It appears that at this high temperature, provided the time factor is sufficiently short, an

60

A characteristic feature of the invention is that under the high temperature conditions, there is a period of pronounced activity for a relatively short time at the beginning of the run producing a considerable increase in the octane number and giving some evidence of polymeriza-

tion, at least polymerization into products of intermediate boiling range. This run exemplifies such results. In the first six-hour period of the run representing a yield of 382 barrels per ton of catalyst, the clear octane number was raised 6.3 points; the distillation test furnishes evidence of some polymerization. After this rather brief period of excessive activity of the fresh catalyst, the operation levels off with no further evidence of polymerization in the distillate product, and while the extent of the octane increase is not as great as in the initial period of excessive activity, a definite increase in octane number and lead response is maintained fairly constant for an extended period of time. This result is unusual and unexpected, in that in prior catalytic desulfurizing operations there is a tendency for the octane number and lead response to be progressively reduced as the run proceeds. In this example of the invention, the run was terminated at the end of 331 hours, representing a yield of 21,000 barrels per ton of clay. The sample taken at the end of the run for the last period had a satisfactory leaded octane number, although the sulfur reduction was low.

In practicing the invention it is desirable to heat the gasoline stock to the desired temperature of reaction as rapidly as possible so as to minimize or avoid any strictly thermal conversion which might take place prior to contacting with the adsorptive clay.

Although a preferred embodiment of the invention has been described herein, it will be understood that various changes and modifications may be made therein, while securing to a greater or less extent some or all of the benefits of the invention, without departing from the spirit and scope thereof.

I claim:

1. The method of treating gasoline stocks for the removal of sulfur and improvement in characteristics as motor fuel which comprises continuously passing the gasoline vapors in contact with an adsorptive clay catalyst for an extended period of time, maintaining the vapors at a temperature of about 900-950° F. in contact with the clay catalyst and maintaining a time of contact of the vapors with the catalyst amounting to approximately 5-15 liquid volumes per hour per volume of catalyst to thereby subject the gasoline vapors to conditions adequate to produce effective conversion of sulfur compounds into hydrogen sulfide and to thereby establish and maintain equilibrium conditions for an extended period of time under which the boiling distribution range of the gasoline remains substantially unaltered and the tendency toward polymerization is offset by reversion to the prepolymerized state to thus prevent substantial raising of the end boiling point of the gasoline being treated and to avoid material deposition on the catalyst of the ultimate products of polymerization so that a desulfurized gasoline product of improved motor fuel characteristics is produced.

2. The method of treating cracked gasoline stocks for the removal of sulfur and improvement in characteristics as motor fuel which comprises continuously passing the gasoline vapors in contact with an adsorptive clay catalyst for an extended period of time, heating the vapors to a temperature of about 900-950° F. for contact with the clay catalyst and maintaining a time of contact of the vapors with the catalyst amounting to approximately 5-15 liquid volumes per hour

per volume of catalyst to thereby subject the gasoline vapors to conditions adequate to produce effective conversion of sulfur compounds into hydrogen sulfide and to thereby establish and maintain equilibrium conditions for an extended period of time under which the boiling distribution range of the gasoline remains substantially unaltered and the tendency toward polymerization is offset by reversion to the prepolymerized state to thus prevent substantial raising of the end boiling point of the gasoline being treated and to avoid material deposition on the catalyst of the ultimate products of polymerization so that a desulfurized gasoline product of improved motor fuel characteristics is produced.

3. The method of treating cracked gasoline stocks for the removal of sulfur and improvement in characteristics as motor fuel which comprises continuously passing the gasoline vapors in contact with fuller's earth for an extended period of time, maintaining the vapors at a temperature of the order of 950° F. in contact with the clay catalyst and maintaining a time of contact of the vapors with the catalyst amounting to approximately 10 liquid volumes per hour per volume of catalyst to thereby subject the gasoline vapors to conditions adequate to produce effective conversion of sulfur compounds into hydrogen sulfide and to thereby establish and maintain equilibrium conditions for an extended period of time under which the boiling distribution range of the gasoline remains substantially unaltered and the tendency toward polymerization is offset by reversion to the prepolymerized state to thus prevent substantial raising of the end boiling point of the gasoline being treated and to avoid material deposition on the catalyst of the ultimate products of polymerization so that a desulfurized gasoline product of improved motor fuel characteristics is produced.

4. The method of treating gasoline stocks for the removal of sulfur and improvement in characteristics as motor fuel which comprises initially passing gasoline vapors for a relatively short period through a bed of adsorptive clay at a temperature of about 900-950° F. and at a flow rate amounting to approximately 5-15 liquid volumes per hour per volume of catalyst to thereby effect reactions involving conversion of sulfur compounds to hydrogen sulfide accompanied with some polymerization to form liquid polymers, continuing the passage of said vapors through the clay bed during said initial period until the formation of polymers is reduced and then continuing the passing of said vapors through the clay bed for an extended period of time under said conditions of temperature and flow rate to thereby continue the subjection of the gasoline vapors to conditions adequate to produce effective conversion of sulfur compounds into hydrogen sulfide and to thereby establish and maintain equilibrium conditions for an extended period of time under which the boiling distribution range of the gasoline remains substantially unaltered and the tendency toward polymerization is offset by reversion to the prepolymerized state to thus prevent substantial raising of the end boiling point of the gasoline and to avoid material deposition on the catalyst of the ultimate products of polymerization so that a desulfurized gasoline product of improved motor fuel characteristics is produced.

DU BOIS EASTMAN.
